SIGNAL CREATING APPARATUS

Charles C. Chenoweth, Abilene, Tex.

Application June 1, 1934, Serial No. 728,598

9 Claims. (Cl. 246—126)

This invention relates to a signal creating apparatus for use at railway grade crossings, and has for its object to provide, an apparatus of the class referred to, under the control of a train approaching the crossing for producing a distinctive warning signal, in the form of a quickly visible body of vapor, at the intersection of a railway track and a road, boulevard or street for warning one travelling towards the intersection that a train is approaching the latter thereby reducing the possibilities of accidents to a minimum.

A further object of the invention is to provide, in a manner as hereinafter set forth, an apparatus of the class referred to under the control of a train approaching a railway crossing for producing a body of vapor and for directing said body upwardly from the crossing to provide a readily visible warning signal to one approaching the intersection of an oncoming train.

Further objects of the invention are to provide, in a manner as hereinafter set forth, an apparatus for the purpose referred to which is simple in its construction and arrangement, strong, durable, readily installed with respect to a railroad crossing and a railway track, thoroughly efficient for the purpose intended thereby, automatic in its operation, inexpensive in maintenance, expeditiously repaired and cleaned when required, and comparatively inexpensive.

To the above ends essentially, and to others which may hereinafter appear, the invention consists of such parts and such combination of parts which fall within the scope of the invention as claimed.

In the drawings:—

Figure 1 is a top plan view showing the apparatus, in accordance with this invention installed with respect to a railroad intersection and a railway track.

Figure 2 is a longitudinal sectional view of a vapor producing structure.

Figures 3 and 4 are longitudinal sectional views of two other forms of vapor producing structures.

Figure 5 is a transverse cross sectional view of another form of vapor producing structure.

Figure 6 is a top plan view illustrating a different position of the grid at the intersection and a different position of the vapor producing structure of the form shown in Figure 2.

The apparatus includes a structure under the control of a train approaching the intersection for producing a body of vapor which is to extend upwardly from the bottom of the intersection and constitute a warning signal to a per-

destrian or the driver of a vehicle approaching the intersection from either side of the latter. The structure referred to may or may not be provided with a blower device for forcing the body of vapor up through the bottom of the intersection. In Figure 2 the vapor producing structure is shown as being provided with a blower device. One vapor providing structure may be of the type to provide for a liquid to come in contact with the atmosphere to produce smoke and such type is shown in Figure 2; another vapor producer may be of that type whereby an electric heating element is floated upon a body of liquid and made active by the train approaching the intersection to produce the vapor and such type is shown in Figure 3; or the vapor producer may be of a type whereby the train approaching the intersection will control a discharge of gas into the atmosphere to produce smoke and this type is shown in Figure 4; or the vapor producer may be of that type including an electric heating element seating on a solid and which is made active by the train approaching the crossing to produce a body of vapor and this type is shown in Figure 5.

Referring to Figures 1 and 2 of the drawings 1 denotes an intersection between a railroad track 2 and a road 3. Mounted between the track members 4, 5 of the track 2 and centrally with respect to the intersection 1, as well as being flush with the level of the latter is an open grating or grid 6. Arranged below the road 3 and extended to below the intersection 1 is an open upper end container body 7 upon which is positioned a flanged lid 8. One end of the latter has a rectangular opening 9 which registers with a vertical passage 10 formed in the bed 11 of intersection 1. The grating or grid 6 is positioned at the top of passage 10.

Supported within the body 7 and above the bottom of the latter is a flared normally closed receptacle 12 having one end provided with an upwardly inclined hollow tapered extension 13 terminating and opening into a closed annular casing 14. The extension 13 provides a flared passage 15 opening into the upper portion of receptacle 12 at one end of the latter. The top 16 of receptacle 12 at the other end of the latter includes an upstanding inclined partition 17 which has its upper end registering with one of the end walls of opening 9. The width of receptacle 12 is substantially the same as body 7. The casing 14 abuts the end 18 of body 7. The ends 19, 20 of the receptacle 12 are spaced from the ends 21, 18 respectively of body 7. The upper part of the end

19 of receptacle 12 is cut away to provide an outlet 22 which is normally closed by a spring controlled gate 23. The receptacle 12 is to communicate with that portion 24 of body 7 which is arranged below opening 9 when gate 23 is open. The partition 17 constitutes a deflector.

Arranged within the casing 14 is a fan 25 which is operated from an electric motor 26 positioned within the upper part of body 7 in proximity to the end 21 of the latter. The motor 26 is interposed in a normally open power circuit 27. Interposed in the latter is a circuit closing means 28 therefor. The means 28 is arranged in juxtaposition to track rail 5 at a point remote from intersection 1 and is actuated by the wheels of a train approaching the latter for the purpose of operating motor 26 to drive fan 25. When fan 25 is operated the gate 23 is forced open against the action of its spring and the liquid 29 in receptacle 12 comes in contact with the atmosphere to produce a body of smoke, the latter constitutes the warning signal, and it is forced by the fan up through the grid 6 at the intersection 1 to constitute a warning to a person or driver approaching the latter. The partition 17 functions to direct the smoke produced in a direction towards passage 10 and prevents the smoke from passing to the rear of the body 7.

With reference to Figure 3 a modified form of vapor producing structure is illustrated consisting of a rectangular container 30 having a top formed of a fixed part 31 and a hinged part 32 of grid like form. Within the container 30 is a closed top receptacle 33 having the end wall 34 thereof cut out to form an outlet 35. Integral with the upper end of wall 34 is an outwardly directed downwardly inclined deflector 36 which is arranged adjacent the outlet 35. Within receptacle 33 is a body of liquid 37 upon the level of which is arranged an electrical heater element 38 made active by the train approaching the intersection to produce in connection with the liquid 37 a body of vapor which passes from the receptacle 33 and into the container 30. The body of vapor is discharged up through the hinged section 32. The container 30 is to be positioned relative to the intersection 1 in the same manner as the container body 7 and with the hinged section located at the bottom of passage 10.

Figure 4 illustrates another modified form of vapor producing structure consisting of a container 39 having a portion of its top in the form of a grid 40 to be located at the bottom of passage 10. Within the container 39 is a tank 41 for a storage of gas. An electrically operated outlet valve structure 42 is provided for tank 41. The structure 42 is controlled by a train approaching intersection 1 for the purpose of opening structure 42 to provide for a discharge of gas from tank 41 into the atmosphere for the purpose of producing smoke which travels up through grid 40 to provide the signal.

With reference to Figure 5 another modified form of vapor producing structure is shown consisting of an electric heating element 43 seated on a solid body 44 of suitable material and made active by the train approaching the intersection 1 to coat with the solid 44 to produce a body of vapor. The body 44 is arranged within a container 45 having a grid 46 at its top to be positioned at the bottom of passage 10.

With reference to Figure 6 the vapor producing structure indicated generally at 47 is of the same form shown in Figure 2. The structure 47 is disposed lengthwise of and below the track 2, as well

as extending below and transversely with respect to intersection 1. In Figure 6 the rectangular grid indicated at 48 is disposed in a direction transversely of the track 2.

Any suitable arrangement may be had for cleaning and filling the vapor producing structures.

What I claim is:

1. In a signal creating apparatus for railroad intersections, a normally inactive electrically operated visible vapor producing means located below the ground level and having an outlet positioned below the intersection, means for conducting the vapor produced by said means from said outlet in a direction to travel upwardly with respect to the level of the intersection to provide a warning signal and including a grid at the level of the latter for the passage of the vapor, and electrical means controlled by a train as it approaches the intersection for making active said vapor producing means.

2. In a signal creating apparatus for railroad intersections, the combination with the bed of the intersection formed with a passage opening at the level of the latter, of a normally inactive visible vapor producing means completely arranged below the ground level and communicating with said passage, and electrical means controlled by a train at a point remote from said vapor producing means as the train approaches the intersection for making active said vapor producing means whereby a body of vapor is formed for discharge through said passage into the atmosphere above the intersection to provide a warning signal.

3. In a signal creating apparatus for railroad intersections, the combination with the bed of the intersection formed with a passage opening at the level of the latter, of a normally inactive visible vapor producing means completely arranged below the ground level and communicating with said passage, electrical means controlled by a train at a point remote from said vapor producing means as the train approaches the intersection for making active said vapor producing means whereby a body of vapor is formed for discharge through said passage into the atmosphere above the intersection to provide a warning signal, and a grid at the outer end of said passage and flush with the level of the intersection.

4. In a signal creating apparatus for railroad intersections, a normally inactive visible vapor producing means located below the ground level and having an outlet positioned below the level of the intersection, means controlled by a train as it approaches the intersection for making active said vapor producing means to provide a warning signal in the form of a body of vapor, and means for conducting the body of vapor from said outlet to extend into the atmosphere above the level of the intersection.

5. In a signal creating apparatus for railroad intersections, a normally inactive visible vapor producing means located below the ground level and having an outlet positioned below the level of the intersection, means controlled by a train as it approaches the intersection for making active said vapor producing means to provide a warning signal in the form of a body of vapor, means for conducting the body of vapor from said outlet to extend into the atmosphere above the level of the intersection, and the said means controlled by the train including a propelling element for the body of vapor.

6. In a signal creating apparatus for road intersections, a normally inactive vapor producing means completely located below the ground level

and having an outlet below the intersection, means controlled by a mobile body as it approaches the intersection for making active said vapor producing means to provide a warning signal in the form of a body of visible vapor, and means for conducting the body of vapor from said outlet to extend into the atmosphere above the level of the intersection.

7. In a signal creating apparatus for road intersections, the combination of a casing completely located below the ground level and having an outlet, a normally inactive visible vapor producing means within said casing, a grid at the level of the road intersection for the passage of vapor into the atmosphere, a conducting passage for the vapor leading from said outlet to said grid, and means controlled by a mobile body as the latter approaches the intersection for making active said vapor producing means.

8. In a signal creating apparatus for road intersections, the combination of a casing completely located below the ground level and having an outlet, a normally inactive visible vapor producing means within said casing, a grid at the level of the

road intersection for the passage of vapor into the atmosphere, a conducting passage for the vapor leading from said outlet to said grid, said vapor producing means including a normally inactive propelling element for the vapor produced by said means when the latter is active, and means controlled by a mobile body as the latter approaches the intersection for simultaneously making active said vapor producing means and element.

9. In a signal creating apparatus for road intersections, a casing located completely below the ground level and provided at its top with an outlet, a normally inactive visible vapor producing means arranged within said casing, a grid arranged at the level of a road intersection in parallel spaced relation to said outlet for the passage of vapor into the atmosphere, a vapor conducting passage leading from said outlet to said grid, and means controlled by a mobile body as the latter approaches the intersection for making active said vapor producing means.

CHARLES C. CHENOWETH.
